Wash., a corporation of Washington

Application July 5, 1947, Serial No. 759,245

11 Claims. (Cl. 144—208)

1

This invention relates to the barking of wood, and has particular reference to improvements in the application of hydraulic jets to a log surface to remove the bark therefrom.

The increasing cost of wood and the expanding utilization of bark products makes it ever more desirable to remove the bark cleanly from the log in a manner that will not waste or damage the wood and will not include wood in the removed bark. Conventionalrossing machines are not capable of removing all the bark and, at the same time, maintaining a clean separation of the bark from the wood, because on irregular logs the action of cutting tools cannot be stopped at the cambium layer. Hydraulic methods are inherently adapted to effect a clean removal of the bark without inclusion of wood chips and slivers, but have been subject to numerous disadvantages in the manners practiced in the prior art.

A considerable amount of power is required to maintain the necessary velocity head in a hydraulic jet to remove thick and tenacious bark from large logs. Such a high velocity stream cannot be turned off and on at frequent intervals, but must be left running in short periods of non-use because the valves cannot be closed and opened quickly and heavy pumping equipment cannot be started quickly. In addition to this limitation it has been found difficult to maneuver the water jet and a large log to remove all the bark and to shift quickly from one log to another without wasting a great amount of water, and consequently prime mover energy. When a jet is moved haphazardly over the log surface some areas receive longer treatment than others, causing a non-uniform removal of bark and a waste of water, and then more water is wasted in moving over barked areas to give further treatment to remaining islands of bark. The small area covered by a jet makes it impractical, if not impossible, to effect a movement, or feed, of the log relative to a stationary jet to apply the jet successfully in a geometrical pattern to give uniform treatment to all points on the surface of a large, irregular log. Even slight irregularities in the log surface are sufficient to cause gaps and overlaps in the barking action resulting in spotty bark removal which makes conventional mechanical feed mechanisms inoperative for hydraulic log barking unless a large percentage of the water is wasted in excessive overlaps. The conventional hydraulic barking operation, therefore, frequently effects a compromise between complete bark removal and excessive wastage of water and time, with the result that patches of bark may be left on the log.

2

In general, the object of the present invention is to provide improvements in the hydraulic barking of wood to make the barking process fast, thorough and economical of water. A primary object is to provide a method of applying one or more jets of water to a moving wood surface in a definite systematic pattern to subject the entire bark area of the wood progressively to substantially uniform jet action without overlapping of different areas of treatment and without leaving any untreated areas. Further objects are to provide a method of application of the hydraulic jets to the bark surface on a log in which one or more jets are oscillated through a predetermined zone of action and the log is moved relatively to the jets to extend the zone of action over the surface of the log, to provide a method wherein one or more hydraulic jets are oscillated longitudinally of the log in coordination with a turning and feeding of the log relative to the jets to remove the bark progressively in a spiral pattern, to provide a method of feeding logs successively through a barking chamber to remove the bark from any number of logs in a continuous operation without wasting water in intervals between successive logs, and to provide novel apparatus for performing the steps of the method.

In applying the present method to logs, the logs to be barked are fed longitudinally and rotated through a zone of jet action in a barking chamber. The logs are fed one after another in this manner with relatively little gap therebetween to reduce the loss of time and water in the spaces between successive logs. In the zone of jet action there are disposed one or more nozzles directed against the log surface at the optimum angle for maximum bark removal. If more than one nozzle is employed, the several nozzles are disposed in a plane preferably at a small angle with a radial plane through the log, and the nozzles are oscillated in their common plane so as to move back and forth lengthwise of the log. The angles of oscillation or traverse of the nozzles are adjusted to produce an elongated zone of action having a length equal to the sum of the lengths of the lines of action of the individual nozzles.

The jets from such nozzles are preferably flattened in a direction perpendicular to the axis of the log and perpendicular to the common plane of oscillation. Thus, when the nozzles oscillate, the jets move in directions at right angles to the planes of the jets to sweep a certain bark area. The log feed in rotation is adjusted so that the area swept by the jets includes new bark surface at each oscillation. Where a single sweep of the jet is sufficient to cleanly remove the bark, the

rotation of the log may be such as to subject an entire new area of bark to jet action at each sweep, but, obviously, the log feed may be adjusted to produce any amount of overlap necessary for complete bark removal. The longitudinal feed rate of the log is coordinated with its rotational movement so that the bark is completely removed in a spiral path in one continuous operation without subjecting any part of the log to secondary treatment.

The method of the invention is best understood with reference to the diagrams and apparatus illustrated in the accompanying drawings, although it is to be understood that other equipment may be devised to perform the steps of the method.

In the drawings:

Figure 1 illustrates diagrammatically the path of motion of a single oscillating hydraulic jet on a developed log surface after the log has made approximately one and one-half revolutions under the action of the jet according to the method of the invention;

Figure 2 is a diagram on an enlarged scale showing bark areas swept on successive oscillations and the pattern of bark removal produced by a single jet having a path of movement on an advancing and rotating log surface as shown in Figure 1;

Figure 3 is a view similar to Figure 1, showing the center line paths of movements of a pair of jets oscillating in opposite directions in a common plane;

Figure 4 illustrates on an enlarged scale the swept areas and bark removal pattern produced by the twin jet arrangement having the movements shown in Figure 3;

Figure 5 is a side elevation view of a log showing the pattern of bark removal either by a single jet, as shown in Figures 1 and 2, or by a series of jets oscillating in a plane, as shown in Figures 3 and 4;

Figure 6 is a plan view of a log barking plant equipped to carry out the present method of hydraulic barking;

Figure 7 is a side elevational view of the plant shown in Figure 6;

Figure 8 is a cross sectional view through the log barking plant shown in Figures 6 and 7;

Figure 9 is a side elevation view of the mechanism for oscillating the nozzles shown in Figures 7 and 8;

Figure 10 is a detail view showing the construction of one of the log supporting trunnion wheels;

Figure 11 is a fragmentary view showing the toothed log supporting and engaging edge of a trunnion wheel; and

Figure 12 is a sectional view taken on the line 12-12 of Figure 10, showing the overriding clutch in the trunnion wheel assembly.

Diagrammatic explanation of the method

In Figure 1 the numeral 10 designates a developed surface portion of a log undergoing treatment in a barking operation according to the method of the invention. Let it be assumed, for purposes of reference and conventional representation, that the log from which the developed surface 10 is taken is being fed longitudinally from right to left through a zone of action of a single oscillating hydraulic jet, and that the log is caused to rotate so as to gradually move the developed surface downwardly with respect to the oscillating jet, as viewed in Figure 1. The

numeral 11 on the left end of the developed surface then designates a bare wood surface from which the bark has just been removed by passage through the zone of action of the barking jet, and the numeral 12 on the right end of the developed surface represents a bark surface which is approaching said zone of action. The broken zigzag line 13 traces the path of movement of the single oscillating jet relative to the log surface as the latter advances and rotates relative to the jet. It is understood that the log is advanced and rotated relatively slowly and that the hydraulic jet is oscillated relatively fast in a direction longitudinally of the log.

Because of the rotation of the log, the center of impact of the jet does not retrace its path on successive oscillations, but advances in the zigzag patterns shown, spirally around the log to subject all the bark on the log progressively to the action of the jet. Thus the jet follows the path of the arrows in the line 13 from a point 14 to a point 15 in one complete rotation of the log. Since the surface 10 is a developed surface, the point 16 coincides with the point 15 on the log, and in the next half revolution of the log the jet traces the zigzag path indicated from the point 16 to the point 17. As the log continues to rotate and advance from right to left, the zigzag path 13 continues in the same manner and the unbarked surface 12 is progressively subjected to the same action. The longitudinal feed rate of the log is coordinated with the amplitude of the jet oscillation so that the longitudinal advance in each revolution is approximately equal to such amplitude whereby the zone of action between the points 16 and 17 lies immediately alongside the zone of action between the points 14 and 15, and so on in successive revolutions.

When the jet is flattened in a vertical plane, the zone of action takes the form shown on a larger scale in Figure 2. The line 20 represents the position and width, or effective vertical height, of the flat stream where it impinges upon the log surface at the left hand limit of movement of the jet on a particular oscillation. The line 21 indicates the position of the stream on the bark at the limit of its next movement in a right hand direction. From the line 21 the stream then moves to the left to the line 22, and then back to the right to the line 23, and so on, to sweep a parallelogram area in each oscillating movement, as shown. The horizontal distance between the two vertical lines 20 and 22 represents the amount of longitudinal movement of the log during one cycle of oscillation of the jet, and the vertical displacement of these two lines indicates the amount of rotational movement of the log in this period of time. It will be observed that there is a substantially complete overlap in the right and left hand movements of the jet, so that the jet is caused to pass twice over each point on the log surface as the jet oscillates and the log revolves. The log feed may be adjusted to provide more or less overlap, as the bark condition may require. For example, the bark may be removed cleanly from some logs without necessity for the jet to impinge upon every small portion of the bark surface, while on other logs several passes may be necessary on each part of the bark surface to remove the bark cleanly from the wood. Also, when different nozzles are used, the log feed may be adjusted to obtain the most efficient barking action.

It is desirable in practice to use two hydraulic jets synchronously oscillating in side by side rela-

tion. Such an arrangement not only extends the zone of barking action to substantially double the rate of bark removal, but also enables the vibrating forces to be balanced in the nozzle oscillating mechanism. The center line paths of movements of dual oscillating jets are shown in Figure 3, wherein the broken line 13 traces the path of motion of one of the jets and the line 13a traces the path of the other jet. It is observed in this diagram that the jets are caused to move always in opposite directions in a common plane of action, and that at the end of each cycle of oscillation they impinge upon the log at closely adjacent points. The two jets thus describe zig-zag spiral paths around the log to extend the zone of action over untreated bark immediately alongside the zone of action in the preceding revolution of the log. The zones of action of the two jets thereby proceed around the log in the manner of a double spiral thread having a lead equal to twice the amplitude of vibration of one of the jets. Preferably, the hydraulic pressure and log feed rates are adjusted so that overlapping with previous zones of action does not occur, but, of course, any amount of longitudinal overlapping may be obtained if desired by slowing up the longitudinal feed rate of the log, just as circumferential overlapping may be obtained by slowing up the rotational feed rate of the log.

When the longitudinal and rotational feed rates of the log are adjusted to produce relative center line paths of movement of the two jets as shown in Figure 3, the zones of action covered by these two jets are represented by the adjoining continuous parallelogram patterns 24 and 25 shown on an enlarged scale in Figure 4. In each oscillating movement each of the jets sweeps through a parallelogram area of action, and the two zones comprising these successive parallelogram areas interfit in the manner shown to produce a total zone of action taking the general form of a spiral band around the log similar to that produced by the single jet in Figure 2.

The barking action produced by the spiral advance of the zone of action around the log is illustrated in Figure 5. The numeral 11 designates bare wood surface from which the bark has already been removed by the longitudinal feeding movement of the log from right to left, and the numeral 12 designates untreated bark which has not yet passed through the zone of hydraulic action. The spiral edge of bark 26 represents a succession of the vertical lines 21, 23 etc., marking the right hand edge of the zone of action. The bark edge 27 represents the advancing end of the zone of action which may be produced by a single jet or by a plurality of jets in the manner described. More than two jets may be employed if desired. Thus the bark is removed in a spiral path around the log in which substantially the same amount of energy is applied to every point on the log to remove the bark cleanly with a minimum amount of water in a minimum time for a given power consumption in the hydraulic system.

In Figures 1 to 5 it is apparent that the log is twisted and advanced in the manner of a bolt with a left hand thread. It will be observed that an important purpose accomplished by the flattening and oscillation of the jet or jets is to extend the zone of action to cover sufficient area so that a mechanical feeding mechanism can be employed effectively without a large percentage of overlap at the margins of the zone of action. Since a log surface is not truly cylindrical it is difficult to provide a fine and accurate feed,

especially in rotation, for use with a small jet. By flattening the jet in a vertical plane the feeding problem is simplified and more uniform surface coverage is assured. The directions of rotation and advance may of course be reversed without departing from the spirit of the invention.

The present method is also applicable to bark surfaces on saw mill slabs and the like, in which case it may be preferable not to move the slabs vertically in conjunction with the horizontal feed, but to alternately elevate and depress the plane of the jets in order to cover the more limited area of the slab. It is, therefore, to be understood that the feed motion to produce the bark removal patterns described hereinabove is merely relative and does not necessarily require the same absolute movements of the wood longitudinally and rotatively that have been described as suitable for log sections.

The barking plant

A hydraulic barking plant for carrying out the method of the invention is illustrated in Figures 6 and 7. During the barking treatment the logs are supported for longitudinal and rotational movements on pairs of obliquely disposed power driven trunnion wheels 30. A plurality of substantially horizontal conveyors 31 form a log deck upon which the logs to be barked may be placed side by side as they are received. A series of retractable stops 32 hold the logs on this deck until they are needed. The conveyors forming the log supporting surface of the log deck are power operated from time to time to move the logs sidewise until the outermost log is crowded against the stops 32. The numeral 33 designates a series of loading chains on lift skids which may comprise arms pivotally mounted for vertical movement on a horizontal shaft 34 which may also carry idler sprockets for the log deck conveyors 31.

Suitable controls are provided for these various mechanisms so that the stops 32 may be retracted to transfer a single log from the deck conveyors 31 to the lift skids 33, on which it is then moved outwardly to a position immediately above the pairs of trunnion wheels 30 while the lift skids are in a raised position as shown in broken lines in Figure 8. By then lowering the outer ends of the lift skids the log is deposited in the trough formed by the trunnion wheels. Pairs of retractable centering arms 35 mounted on central pivots 36 are provided to align the log with the pairs of trunnion wheels as the lift skids are lowered. After the log is deposited in this manner on the trunnion wheels, the lift skids are dropped out of the way as shown in full lines in Figure 8 so that the log rests solely upon the trunnion wheels. The centering arms may, if desired, be maintained in positions just out of engagement with the log to serve as guards against accidental displacement of the log from the trunnion wheels.

Rotation of the trunnion wheels serves to advance the log from right to left, as viewed in Figures 6 and 7, and to rotate the log in the manner of a bolt with a right hand thread. Means will hereinafter be described for adjusting the angles of the trunnion wheels to change the rate of longitudinal feed of the log in relation to its rate of rotation. As the log is advanced longitudinally on the trunnion wheels it gradually approaches the zone of action of hydraulic barking jets which are projected and oscillated through an elongated opening 38 in a shield 37 extending longitudinally beneath the under surface of the

log. The handling of the logs and the barking action are observed and controlled from an operator's room 40 having windows overlooking the log deck and the hydraulic jets. A back wall 41 and a top shield 42 form a barking chamber to confine the water and the bark which leave the log at high velocities. Under the barking chamber is a pit 43 having a drainer bottom and a refuse conveyor 44 to carry away the bark.

In Figure 7 a log 45 is shown passing through the barking chamber on the trunnion wheels 30. This log was lowered on the trunnion wheels in the position indicated at 45a, and the lift skids 33 were then dropped to the position shown, where they remain until they are raised to transfer another log from the log deck to the trunnion wheels. When the trailing end of the log 45 is in a position to clear the leading end of the next log on the log deck, the latter will be transferred to the trunnion wheels to closely follow the log 45 with as little space as practicable between the two logs. Short logs may be loaded on the log deck and lift skids near the left end as viewed in Figures 6 and 7 so that the lift skids will not interfere with the log already in the barking chamber when they are raised to receive a new log to follow closely the preceding log.

With the trunnion wheels set at the angles shown in Figures 6 and 7, each wheel makes a real or imaginary track on the log substantially as indicated by the broken spiral line 46, as the log is rolled and advanced through the barking chamber. The hydraulic barking jets issue from a pair of nozzles 50 and 51 pivotally mounted on spaced parallel pivots 52 and 53. The nozzles are connected to links 54 and 55 for oscillation through the respective angles indicated at 56 and 57 to cause their jets of water to sweep longitudinally over the log through a combined distance approximately equal to the lead of the trunnion wheel track 46. A pair of hold down wheels 60 are resiliently mounted over the trunnion wheels 30 in the barking chamber to hold the log down against the lifting force of the jets. Water is supplied to the nozzles under extremely high pressure through the flexible hose connections 58.

Nozzle oscillating mechanism

One form of nozzle oscillating mechanism is shown in Figure 9. A double acting hydraulic cylinder 61 contains a piston on a piston rod 62 having a rigid fitting 63 pivotally connected with a pair of links or shackles 64. A pair of walking beams 65 pivotally mounted at 66 have adjacent inner ends connected with the shackles 64 and outer ends connected with the links 54 and 55 to oscillate the nozzles through the desired angles 56 and 57, with the movements of the two nozzles always being in opposite directions. This motion is transmitted to a pair of nozzle pipes 68 through a plurality of arms 67 forming a triangular truss of sufficient strength to allow the nozzles to be oscillated at a relatively high frequency of vibration.

A special valve mechanism 70 is provided to reverse the piston quickly at each end of its stroke in order to move the nozzles at a substantially uniform rate in all parts of the oscillation cycle. The valve 70 comprises a hollow hydraulically balanced piston member 71 connected with a piston rod 72 which carries a connecting yoke 73 for slidably receiving a pin 74 on one of the beams 65. The pin 74 is provided with a pair of adjustable stops 75 and 76 to move the

valve piston in opposite directions as the nozzles closely approach their limits of movement. Pipes 77 and 78 connect the opposite ends of the actuating cylinder 61 with respective annular chambers 79 and 80 in the valve cylinder. A water inlet pipe 81 is in communication with a central annular chamber 82. An outlet pipe 83 is in direct communication with the annular chamber 80 when the valve piston is in the position shown, and in communication with the annular chamber 79 through the hollow valve piston when the latter is moved to the other end of the valve cylinder. The outer surface of the valve piston is reduced in its central portion so that when it is in the position shown the annular inlet chamber 82 is connected with the annular chamber 79 to supply water under pressure to the pipe 77 to move the piston rod 62 outwardly.

As the piston rod 62 moves outwardly, water from the other end of the cylinder 61 returns through pipe 78 to the annular chamber 80 and is discharged through pipe 83. During the outward movement of piston rod 62 the pin 74 slides freely in the connecting yoke 73 until near the end of the stroke, at which time the stop 75 engages the yoke 73 to move the valve piston 71 quickly to the other end of the valve cylinder. The new position of the valve piston 71 then places the water pressure inlet chamber 82 in communication with the chamber 83 and pipe 78 to move the piston rod 62 inwardly and discharge water from the lower end of cylinder 61 through pipe 77, annular chamber 79, the interior of valve piston 71, and pipe 83. As the piston rod 62 moves inwardly the pin 74 slides freely in the connecting yoke 73 until near the end of the stroke, whereupon the stop 76 engages the connecting yoke to quickly return the valve piston to the position shown for a new cycle. The yoke 73 thereby functions as a lost motion connection between the valve mechanism and the nozzle linkage to minimize throttling in the valve action so that the nozzles will swing at a uniform speed from the beginning to the end of each stroke. The vibratory forces created by the quick reversal of the nozzles are balanced because the forces are always exerted in opposite directions at the same instant. Suitable resilient means can also be provided to cushion the shock at the limits of movement of each nozzle to reduce vibration in the apparatus.

As viewed in Figure 8, the center line 85 of the jet from nozzle 50 may be considered to represent an edge view of the common plane of action of both nozzles 50 and 51 as they swing on their parallel pivots 52 and 53. This plane of action is preferably directed at an angle of approximately 21° with the vertical to intersect the substantially horizontal central bottom surface of the log in the manner shown. Thus, as the log is caused to rotate in the direction of the arrow 86, the bark is turned against the stream for the most effective barking action. This angle is not critical, however, and the streams may be directed at other angles or perpendicularly against the bark surface if desired.

This mounting arrangement of the nozzles insures that they will remain in substantially the same position with respect to the bottom surface of the log regardless of the size of the log. It is apparent that the under surface of a very large log will be only slightly higher and that the under surface of a very small log will be only slightly lower than the under surface of the log 45 shown in Figure 8. Thus the nozzles are always working

at their most effective distance from the bark surface. Moreover, the centering action of the trunnion wheels 30 insures that logs of all sizes will be centered in the same vertical plane to maintain the same angle between the bark surface and the plane of oscillation of the jets. The trunnion wheels 30 thereby establish a reference position for that portion of the log surface which is being acted upon by the hydraulic jets, and so whether the logs be large or small the surface portions to be treated are brought into substantially the same reference positions for the most effective jet action.

A movable shield 87 may be mounted between the zones of action of the two jets to be swung into a position to intercept or deflect one of the jets when the log surface is sufficiently remote to cause objectionable overlapping or conflict between the jets as they approach each other. This shield is shown in retracted position in Figure 9.

The nozzles are preferably designed to produce jets of water which are flattened parallel with the plane of the view in Figure 8 and perpendicular to the plane of the view in Figure 9 to sweep parallelogram areas of the log surface as shown in Figure 4. Other forms of nozzles and oscillating mechanism may be used, however, to practice the method of the invention.

Trunnion wheel construction

The details of construction of the log supporting trunnion wheels are best shown in Figure 10. Each trunnion wheel 30 is carried by trunnions 90 in a yoke member 91 which is mounted on a base 92 for rotation in a fixed base member 93. A bearing member 94 between these two members assumes the thrust and other loads imposed by the weight of the log. A lever arm extension 95 on the rotatable base 92 provides for adjusting the angle of lead of the trunnion wheel, and the levers 95 on the several trunnion wheel assemblies are interconnected by links 96 so that the lead will be the same on all the trunnion wheels and so that they may all be shifted in unison by a single adjusting mechanism.

The links 96 extend through the length of the barking plant as shown in Fig. 6, and are pivotally connected to the opposite ends of a beam 97 mounted on a central pivot 98 so that when one of the links is moved in one direction the other link will move an equal amount in the opposite direction. The links are thus shifted to provide the desired angle of lead in trunnion wheels 30, as shown diagrammatically in Fig. 6.

Each trunnion wheel carries a bevel ring gear 100 driven by a bevel pinion 101 on one end of a shaft 102. The other end of the shaft 102 carries an overriding clutch 103 by which the shaft is driven from a ring gear 104 which is in turn driven by a pinion 105 on one end of a shaft 106. The shaft 106 is concentric with the bearing 94 and carries on its outer end a bevel gear 107 driven by a bevel pinion 108 on a shaft 110 extending the length of the barking plant shown in Figure 6. By means of similar bevel gear drives a pair of the shafts 110 arranged as shown in Figure 8 are adapted to drive all the trunnion wheels at the same speed. The two shafts 110 are in turn driven by chain and sprocket wheel drives 113 (Figure 6) from a single prime mover 114 at variable speeds under the control of the operator in the operator's room. The numeral 111 designates a splash guard to enclose the gears 100 and 101 and one of the trunnion bearings.

The other trunnion bearing is protected by packing 112.

The overriding clutch may be of any approved form, a specific construction being illustrated in Figure 12. In this construction the shaft 102 carries a member 115 having a plurality of balls 116 or other wedging members disposed in individual recesses 117 enclosed by a hub 118 on the gear 104. The wedging members 116 are spring 10 pressed into wedging engagement between sloping walls of the recesses and the hub 118 so that when the latter is rotated in a clockwise direction a positive driving connection is established between the ring gear 104 and the shaft 102. The 15 shaft 102 is always free to rotate faster than the hub 118, because in such case the wedging members 116 are pushed back into the deeper portions of the recesses 117 to allow relative motion in one direction between the member 115 and the hub 118. Inasmuch as the logs carried by the trunnion wheels are not truly cylindrical, the different surface speeds on different parts of the log tend to drive certain of the trunnion wheels faster than they are driven by their prime mover, and 20 the present overriding clutch mechanism accommodates this difference in relative surface velocities of the log without causing the log to slip on the trunnion wheels or climb out of the trough between the trunnion wheels.

25 The trunnion wheels are provided with teeth 120, as shown in Figure 11, to engage the log at each point of support and cause it to rotate with the trunnion wheels. These teeth inflict relatively little damage on a log, even after it has been 30 barked, because of the uniformity of the angle of lead in all the trunnion wheels and the overriding clutches permitting the trunnion wheels to be driven by the log when the surface speed of any part of the log exceeds the peripheral driven 35 speed of the trunnion wheels.

The two hold down wheels 60 are preferably positioned immediately over the two pairs of trunnion wheels in the barking chamber. If desired, these wheels may be mounted to caster 45 on the log to follow the angle of lead set into the trunnion wheels. In Figure 8 the hold down wheel 60 is shown mounted on a vertically movable member 125 which may be raised on a guide 126 to pass a new log thereunder and then lowered to bear on the log with a force sufficient to 50 counteract the lifting force of the barking jets. The hold down force applied to the wheel 60 is preferably exerted by some resilient means, such as compressed air in a cylinder, to allow the wheel 55 to rise and fall over the irregularities of the rotating log. Such a resilient force may be applied in any convenient manner, such as by a piston rod 127, and the member 125 may be vertically 60 slidable or pivotally mounted to provide a sufficient range of vertical movement for the wheel 60.

65 It is to be understood that the method of the invention is not to be limited by the use of a particular apparatus, the present barking plant being shown and described merely for the purpose of illustration and not for the purpose of limiting the invention. The invention is to be limited only by the scope of the appended claims.

70 Having now described my invention and in what manner the same may be used, what I claim as new and desire to protect by Letters Patent is:

75 1. In an hydraulic log barking apparatus, a pair of nozzles mounted for oscillation in a common plane, a fluid cylinder and piston for

11

oscillating said nozzles, means for reversing said nozzles quickly at the end of each stroke to cause said nozzles to move at substantially constant speed throughout each stroke, and a linkage interconnecting said piston and said nozzles and including means for moving said nozzles always in opposite directions in a manner to reduce vibration in the apparatus.

2. In hydraulic log barking apparatus, log-holding means having a spiral feed movement, a nozzle mounted for oscillation in a plane intersecting the longitudinal axis of the log-holding means, a balancing mass mounted for oscillation in said plane relative to said nozzle, power-operated means operatively connected to said nozzle for oscillating said nozzle rapidly in said plane, the nozzle and balancing mass being on opposite sides of said power-operated means, means for reversing said nozzle quickly at the end of each oscillatory movement to cause the nozzle to move at substantially constant speed throughout each movement, and a mechanical linkage interconnecting said nozzle, said power-operated means, and balancing mass for moving said nozzle and mass always in opposite directions toward and away from each other in said plane to reduce vibration.

3. In hydraulic log barking apparatus, log-holding means having a spiral feed movement, a first nozzle mounted for oscillation in a plane intersecting the longitudinal axis of the log-holding means, a second nozzle mounted for oscillation in said plane relative to said first nozzle, power-operated means operatively connected to said nozzles for oscillating said nozzles rapidly in said plane, means for reversing said nozzles quickly at the end of each oscillatory movement to cause the nozzles to move at substantially constant speed throughout each movement, and a mechanical linkage interconnecting said nozzles and said power-operated means to move said nozzles always in opposite directions toward and away from each other in said plane to reduce vibration.

4. In hydraulic log barking apparatus, log-holding means having a spiral feed movement, a nozzle mounted for oscillation in a plane intersecting the longitudinal axis of the log-holding means, a balancing mass mounted for oscillation in said plane relative to said nozzle, power-operated means operatively connected to said nozzle for oscillating said nozzle rapidly in said plane, the nozzle and balancing mass being on opposite sides of said power-operated means, means for reversing said nozzle quickly at the end of each oscillatory movement to cause the nozzle to move at substantially constant speed throughout each movement, said reversing means including a valve mechanism and stop members, and a mechanical linkage interconnecting said nozzle, said power-operated means, and balancing mass for moving said nozzle and mass always in opposite directions toward and away from each other in said plane to reduce vibration.

5. In an hydraulic log barking apparatus, a pair of nozzles mounted for oscillation in a common plane, a fluid cylinder and piston for oscillating said nozzles, means for reversing said nozzles quickly at the end of each stroke to cause said nozzles to move at substantially constant speed throughout each stroke, said reversing means including a valve mechanism and stop members, and a linkage interconnecting said piston and said nozzles and including means for moving said nozzles always in opposite directions

12

in a manner to reduce vibration in the apparatus.

6. In an hydraulic log barking apparatus, a pair of nozzles mounted for oscillation in a common plane, means for oscillating said nozzles, means for reversing said nozzles quickly at the end of each stroke to cause said nozzles to move at substantially constant speed throughout each stroke, said reversing means including a valve mechanism and stop members, and a linkage interconnecting said first-named means and said nozzles and including means for moving said nozzles always in opposite directions in a manner to reduce vibration in the apparatus.

7. In an hydraulic log barking apparatus, a pair of nozzles mounted for oscillation in a common plane, a fluid cylinder and piston for oscillating said nozzles, means for reversing said nozzles quickly at the end of each stroke to cause said nozzles to move at substantially constant speed throughout each stroke, a linkage interconnecting said piston and said nozzles and including means for moving said nozzles always in opposite directions in a manner to reduce vibration in the apparatus, and means for simultaneously advancing and rotating the log being barked.

8. In an hydraulic log barking apparatus, a pair of nozzles mounted for oscillation in a common plane, means for oscillating said nozzles, means for reversing said nozzles quickly at the end of each stroke to cause said nozzles to move at substantially constant speed throughout each stroke, said reversing means including a valve mechanism and stop members; a linkage interconnecting said first-named means and said nozzles and including means for moving said nozzles always in opposite directions in a manner to reduce vibration in the apparatus, and means for simultaneously advancing and rotating the log being barked.

9. Hydraulic barking apparatus comprising a flattened nozzle for delivering a flattened jet of water, a pivotal mounting for said nozzle having its pivotal axis substantially parallel to the plane of said flattened jet, means for oscillating said nozzle on said pivotal mounting, means for reversing the movement of said nozzle quickly at the end of each oscillatory stroke, pivotal oscillatory means operatively connected with said nozzle oscillating means and located oppositely to said nozzle for opposed movement to balance the vibratory forces of oscillation, and means for simultaneously rotating and advancing the log being barked.

10. Hydraulic barking apparatus comprising a nozzle for delivering a jet of water, a pivotal mounting for said nozzle, means for oscillating said nozzle on said pivotal mounting, means for reversing the movement of said nozzle quickly at the end of each oscillatory stroke, pivotal oscillatory means operatively connected with said nozzle oscillating means and located oppositely to said nozzle for opposed movement to balance the vibratory forces of oscillation, and means for simultaneously rotating and advancing the log being barked.

11. In a hydraulic log barking apparatus, a pair of nozzles mounted for oscillation relative to each other in a common plane, power-operated means including a fluid cylinder and piston for oscillating said nozzles rapidly in said common plane, and a linkage system between said power-operated means and each of said nozzles to move said nozzles always in opposite

13

directions toward and away from each other in a manner to reduce vibration in the apparatus.

MILES LOWELL EDWARDS.
